INVENTOR:
Oscar L. Smith
BY ADOLPH Haines,
ATTORNEY

UNITED STATES PATENT OFFICE.

OSCAR L. SMITH, OF RYDAL, PENNSYLVANIA, ASSIGNOR TO PENN RIVET CORPORATION, OF PHILADELPHIA, PENNSYLVANIA, A CORPORATION OF VIRGINIA.

HAIR CURLER.

Application filed March 22, 1923. Serial No. 626,942.

To all whom it may concern:

Be it known that I, OSCAR L. SMITH, a citizen of the United States, residing at Rydal, in the county of Montgomery and State of Pennsylvania, have invented an Improvement in Hair Curlers, of which the following description, in connection with the accompanying drawings, is a specification, like characters on the drawings representing like parts.

This invention relates to improvements in hair curlers for curling or waving hair, and more particularly has reference to hair curlers of the type comprising two arms and formed of a single piece of metal with a locking device for holding the free ends of the two arms in closed position when the hair has been wound upon one of the arms.

One of the objections heretofore experienced in hair curlers of this type has been that the arm on which the hair was wound has been usually formed of flat metal, or at least of metal having well-pronounced or sharp edge portions which are calculated to cut or injure the hair when it is wound thereon and the two members of the curler are brought into locking position. On the other hand, it is desirable to have at least one member of the curler formed of flat metal in order to get a broad locking bearing of the arm upon the mass of hair wound upon the other arm.

One of the objects of the present invention, therefore, is to provide a hair curler of the general type referred to, wherein the hair receiving portion of the curler shall be formed of a stiff or substantially unyielding rod of rounded contour in cross-section on which the hair may be wound, and a flat and flexible member for holding the hair properly wound upon the rounded stiff rod.

The curler of the present invention, therefore, consists of a single piece of metal, comprising a stiff rod of rounded contour on which the hair may be wound, a flat flexible member, and in which also the metal of the stiff rod is flattened at one end to form a spring loop connecting one end of the arms. In thus forming the curler, the flattened metal of the hair receiving stiff rod also provides a shoulder adjacent one end of the rod which acts as a stop to prevent the hair from bodily movement longi-

tudinally of the stiff rod towards the spring loop.

The various features of the invention will best be made clear from the following description and accompanying drawings, wherein:

Fig. 1 is a perspective view of a hair curler embodying features of the present invention;

Fig. 2 is a top or plan view showing more particularly the flattened and widened portion of metal extending from the rod and merging into the flat metal of the flexible arm;

Fig. 3 is a view showing the hair wound upon the curler and the free ends of the curler arms brought into interlocking engagement;

Fig. 4 is an illustration of the blank form from which the hair curler is formed.

In accordance with the present invention, the hair curler is formed of a single piece of metal comprising a hair receiving portion or stiff rod 1 and a flat flexible arm or portion 2 which is connected to the rod 1 by a spring loop 3.

The hair receiving rod 1 is rounded in cross-section so as to present no edge portions whatsoever which might be calculated to cut or injure the hair wound upon the rod. Preferably the hair receiving rod 1 is formed of circular cross-section but of course it might be elliptical without departing from the purpose of the present invention. As hereinbefore stated, the hair receiving rod 1 is stiff, that is, in its intended use, and even when hair is wound upon the rod and the flexible arm is clamped to hold the hair upon the rod, there is no substantial give or flexure of the hair receiving rod.

As hereinbefore noted, the hair receiving rod is integrally formed with the flexible arm 2 which is flat and preferably wider than the diameter of the hair receiving rod 1, as indicated in Fig. 2.

The metal of the hair receiving rod 1 is flattened at one end, as indicated at 4, and is provided with the outwardly extending shoulder portions 5 which gradually merge into the wider flexible arm 2 and form between the arm 2 and the stiff hair receiving rod 1 the spring loop 3. When the hair is wound upon the hair receiving rod 1, the outwardly extending shoulder or stop

portions 5 serve to limit the bodily movement of the hair longitudinally of the hair receiving rod in one direction, and of course when the two members of the hair curler 5 are locked together as will presently be described, bodily movement of the hair on the hair receiving rod in the opposite direction will be prevented.

The flat flexible member 2 is provided 10 with a locking end 6 which is preferably formed by a down-turned portion at the free end of the arm 2, which has a recess 7 of an appropriate size to engage the rounded end portion 8 of the stiff or receiving rod 1 when the free end portions of the rod and arm 2 are brought into locking engagement, as indicated in Fig. 3.

In accordance with the present invention, 20 the hair curler may be variously formed to embody the essential characteristics thereof, but in the present instance the hair curler is made from a blank, as indicated in Fig. 4, in which one portion of the blank is formed as a rod, preferably round or oval 25 in cross-section, and the other portion of the blank is formed as a flat and widened portion, the two being joined by the inclined connecting metal portion. The rounded rod portion of the blank constitutes the hair receiving rod 1 when the curler is finally 30 completed, while the wider flattened portion 2 constitutes the flexible arm 2 of the curler, when the metal blank is bent to form the spring loop 3. Between the rod 1 and 35 flexible portion 2 the metal of the rod 1 is flattened or flared outwardly as at 5, Fig. 4, to constitute the portion 4 which gradually merges into the width of the flexible portion 2.

40 Since the hair receiving rod 1 is of circular or rounded shape in cross-sectional contour and is stiff and substantially unyielding without abrupt edge portions, hair

even of the finest texture, may be wound thereon without injury thereto, and the 45 flattened metal at one end of the rod provides not only a substantial and reliable spring loop portion when the parts of the blank are bent into shape, but affords a stop or shoulder to prevent movement of 50 the hair bodily in a direction longitudinally of the rod.

What is claimed is:

1. A hair curler formed of a single piece 55 of spring metal and comprising a flat flexible arm and a solid stiff hair receiving rod of rounded contour in cross-section and presenting no edges liable to break or injure the hair wound thereon, the metal of the hair receiving rod being flattened and widened beyond the diametrical dimension of the rod at one end and merging into the flat flexible arm to form a widened stop shoulder for limiting the movement of the hair longitudinally of the stiff rod and a 60 spring loop connecting the flexible arm and stiff rod, and a lock for connecting the free ends of the flexible arm and stiff rod.

2. A hair curler formed of a single piece 70 of spring metal and comprising a flat flexible arm and a stiff hair receiving rod substantially round and solid in cross-section and presenting no edge liable to injure the hair wound thereon, the metal at one end of the hair receiving rod being flattened 75 and expended laterally into a part wider than the diameter of the rod to form a spring loop and hair stop between the stiff rod and flat flexible arm, and a locking recess formed on the free end of the flat 80 flexible arm to receive and protect the end of the stiffened rod.

In testimony whereof, I have signed my name to this specification.

OSCAR L. SMITH.
